Inventor:

Josiah Vavasseur

United States Patent Office.

JOSIAH VAVASSEUR, OF SOUTHWARK, ENGLAND.

Letters Patent No. 90,323, dated May 18, 1869; patented in England, November 2, 1868.

IMPROVEMENT IN LOCKS FOR ORDNANCE.

The Schedule referred to in these Letters Patent and making part of the same.

To all to whom it may concern:

Be it known that I, JOSIAH VAVASSEUR, of the London Ordnance-Works, Bear Lane, Southwark, England, a subject of the Queen of Great Britain, have invented or discovered new and useful "Improvements in Apparatus for Discharging Ordnance;" and I, the said JOSIAH VAVASSEUR, do hereby declare the nature of the said invention, and in what manner the same is to be performed, to be particularly described and ascertained in and by the following statement thereof; that is to say—

This invention has for its object improvements in apparatus for discharging ordnance.

When a piece of ordnance is discharged by means of a vent which is left open during the explosion, flame and gases, resulting from the explosion, rush from the bore of the gun into the vent-passage. The vent thus becomes enlarged, and the bore of the gun, close to where the vent enters, becomes starred or cracked, and the gun often ultimately becomes unserviceable from this cause alone. To avoid this injury to the vent-passage, I provide for the firing of the charge, while the vent is closed, in the following manner, which is also advantageous, because it causes a large volume of flame to be instantaneously thrown among the charge to be ignited:

I introduce into the outer end of the vent, which is suitably chambered to receive it, a capsule, like the case of a cartridge for a breech-loading rifle.

This capsule is provided with a percussion-priming, and is loaded with a charge of gunpowder, or similar explosive material, sufficient to produce the volume of flame required.

The capsule is held in the chamber of the vent, so that it may not blow back on firing, by means of a suitable cover to the vent, strong enough to resist the pressure of the gas.

This cover is also fitted with a needle or striker, for exploding the priming of the capsule.

I arrange the cover to slide from one side on to the head of the vent-piece, so as to allow the capsule to be withdrawn.

This cover may be dovetailed, so as to hold it securely.

When the cover is in its place, the needle or striker, which it carries, stands truly over the priming of the cartridge, and the piece is fired by liberating a spring-hammer, which may also be mounted on the cover, so as to allow it to descend on the needle or striker.

The liberation of the hammer may conveniently be effected, by drawing out a pin or stop, by means of a lanyard or cord.

On the discharge taking place, the pressure of the gas inside the capsule hermetically closes the vent, just in the same way as the breech of an ordinary military rifle is closed gas-tight, by the cartridge-case, against the gases produced by the explosion.

An extractor is provided, in connection with the chamber of the vent, to eject the capsule after firing.

And, in order that my said invention may be most fully understood, and readily carried into effect, I will proceed to describe the drawings hereunto annexed.

Description of the Drawings.

Figure 1 is a vertical section of the apparatus, together with a portion of the piece of ordnance to which it is fixed.

α is a vent-piece, which is screwed, as is shown, into a passage formed for it in the gun or piece of ordnance. It is lined with a copper tube, and its end, which is within the bore, is tipped with copper.

A plan of the part α is shown separately at Figure 2. It has a head, α' , of a dovetail-form, in the centre of which is a cavity or chamber, α^2 , to receive a capsule.

This chamber is formed somewhat like the cartridge-chamber at the rear end of the barrel of a breech-loading rifle or fowling-piece, and it is fitted with an extractor, α^3 .

The chamber α^2 receives a metallic capsule, charged with powder or other suitable explosive substance, and provided, at its base, with a percussion-cap, or similar fulminator.

b is a cover, to secure the capsule in its chamber. It is shown separately in plan, Figure 3.

This cover is able to turn on the centre-pin b^1 , carried by an arm of the vent-piece α ; and it fits to the dovetailed head of the vent-piece. It is turned to one side, as is shown by the dotted lines in fig. 2, to uncover the chamber α^2 , for the introduction of the capsule; and, when the capsule has been inserted, and the cover is replaced, the striker b^2 , which the cover carries, stands vertically over the capsule, so that, when forced down, it strikes it at the centre of its base, where the fulminate is situated.

The striker is a pin, with a flange upon it, fitted into a cavity in the cover, and there secured by cap b^3 .

A spiral spring holds the striker up off the capsule until it is forced down by the hammer c .

This hammer turns, at c' , on a pin carried by the cover b , and a spring, as is shown, acts on the tail of the hammer, tending constantly to force it against the striker b^2 .

The hammer is raised by means of a handle with which it is furnished. It is secured by a pin, d , inserted into a socket formed at the top of the centre-pin b^1 ; and the tail of the hammer then bears upon it.

A lanyard is attached to the pin d , and, when it is desired to fire the piece, by a sudden pull on the lanyard, the pin is drawn out of the socket, and the hammer is liberated, so that it may descend on the striker, and explode the capsule.

In some cases, the spring acting on the hammer may be dispensed with, and the hammer be directly

actuated by the lanyard, in the manner shown at Figure 1X.

*b*⁴ is a stop-screw, fixed in the cover *b*. Its end enters a groove in the vent-piece *a*, so as to limit the motion of the cover to the distance required.

*a*³ shows the extractor, and the way in which it is applied. It consists of a lever, fitted in a recess in the face of the head *a*¹, and turning on a centre.

On one end of the lever, the flange of the capsule rests. The other is widened out, to form a thumb-piece, and is pushed down when the capsule is to be extracted; or the extractor may be arranged to receive its motion automatically from the cover.

A capsule, such as I prefer to employ, is shown to an enlarged scale at Figure 4.

The tubular part of the capsule I make of copper, and it is connected with an iron disk or head by a "hat-cap," or hollow rivet, containing a percussion-cap and anvil.

There is a *papier-maché* wad within the capsule, serving both to render the connection between the parts more secure, and to protect the angles around the base of the capsule.

The construction of the capsules may be varied, and they may be made with the fulminating-material placed centrally, or in the rim of the base; or the capsule may be made to fire the fulminating-material by a pin.

By the use of my invention, not only is the rapid wear of the vent prevented, but the necessity of "servicing the vent," or stopping with the thumb during loading, is avoided, and all chances of accident, arising

from this operation being imperfectly performed, are removed.

In applying my invention to cast-iron guns, it will not be necessary to have a vent-tube passing through the metal of the gun. The vent, for the greater part of its length, may be simply drilled in the gun itself. In other ways, the arrangements may be varied, without departing from the invention.

Having thus described the nature of the said invention, and the manner of performing the same, I would have it understood, that I claim, as my improvements in apparatus for discharging ordnance—

1. The combination of the dovetailed vent-piece with the horizontally-moving cover, the combination being and operating substantially as set forth.

2. The combination, with the horizontally-moving cover, of the firing-pin and its spring, to prevent accidental explosions, as set forth.

3. The combination of the vent-piece, capsule-chamber, and its extractor, the combination being and operating as set forth.

4. The combination of the vertically-moving hammer with the horizontally-moving cover, both swinging on a common axis, to clear the vent, as set forth.

5. The combination of the cover, the hammer, the spring, and the trigger, all mounted on the vent-stopper, as set forth.

JOSIAH YAVASSEUR.
